UNITED STATES PATENT OFFICE.

GEORGE D. YOUNG, OF NEW YORK, N. Y.

CARPENTER'S PLANE.

1,202,256.

Specification of Letters Patent. Patented Oct. 24, 1916.

Application filed September 30, 1915. Serial No. 53,205.

To all whom it may concern:

Be it known that I, GEORGE D. YOUNG, a citizen of the United States, and residing at New York, in the county of New York and State of New York, have invented certain new and useful Improvements in Carpenters' Planes, of which the following is a specification, such as will enable those skilled in the art to which it appertains to make and use the same.

This invention relates to carpenters' planes, and the object thereof is to improve the stock or framework of a device of this class and also the bridgework, the blade construction and the construction of the parts used in connection with the blade together with the handle construction, and means for attaching and detaching the handle so as to facilitate the use and operation of the plane and the packing thereof in a small space for shipment or other purposes when desired; a further object being to improve the plane construction so as to make the same strong and durable and so that it will not frequently get out of order and need repair, and so that it will not be broken or injured by the dropping and falling thereof from a work table or bench which frequently occurs with tools of this class.

The invention is fully disclosed in the following specification, of which the accompanying drawings form a part, in which the separate part of my improvement are designated by suitable reference characters in each of the views, and in which:—

Figure 1 is a longitudinal central section of a plane made according to my invention and showing all the parts assembled, the section being on the line 1—1 of Fig. 2; Fig. 2 a plan view thereof; Fig. 3 a view similar to Fig. 1 but showing only one end portion of the device and showing the same on an enlarged scale; Figs. 4, 4^a, and 4^b perspective views of the separate parts of the bridge-work or blade support detached; Fig. 5 a perspective view of the blade and a supplemental cap or wedge plate connected therewith; Fig. 6 a perspective view of a handle securing plate which I employ; Fig. 7 a plan view showing a part of the main frame or stock, a part of the blade support or bridge work and other details with part of the construction broken away and part in section; Fig. 8 a partial section on the line 8—8 of Fig. 1; Fig. 9 a partial section on

the line 9—9 of Fig. 3; and, Fig. 10 a section on the line 10—10 of Fig. 2.

In the practice of my invention, I provide a frame or stock, comprising a main bottom or body part *a*, consisting of a flat horizontal base plate *a*² and raised side plate members *a*³, all of which are stamped from sheet metal and formed integrally, and said frame or stock is provided forwardly of the center thereof, in the construction shown, with the usual blade support or bridge work *b* which is rigidly secured therein and which is made up of separate parts shown detached in Figs. 4, 4^a and 4^b. Fig. 4^a involving two of said parts and also a part of the means for adjusting the blade. One of the parts of the blade support or bridge work consists of a transverse reinforcing member *b*² also stamped from sheet metal and triangular in cross section, and composed of a front transverse side portion *b*³ and a back transverse side portion *b*⁴ arranged at an angle of ninety degrees to each other, and in the apex of said reinforcing member is a transverse slot or opening *b*⁵.

The reinforcing member *b*² is welded to the bottom member *a*² of the stock or frame and to the side members *a*³ thereof, and secured to the front side portion *b*³ thereof and ranging upwardly and backwardly at an angle of approximately forty-five degrees is a plate *c* which supports the blade, and the parts connected therewith, and which is composed of two similar side members *c*², as clearly shown in Fig. 4^a and which are L-shaped in cross section, or provided at their inner edges with downwardly and backwardly directed flanges *c*³ which fit in the slot or opening *b*⁵ in the transverse reinforcing member *b*², and between which is secured a block *d* shown detached in Fig. 4, this connection being made by means of rivets *d*² which are passed through suitable holes *d*³ in the block *d*, and in the flanges *c*³ of the parts *c*² of the plate *c*, but the block *d* may be welded or otherwise secured between the plate members *c*² and the flanges *c*³ thereof.

In connecting the block *d* and the plate members *c*², said plate members are moved forwardly and said block member backwardly so that the flanges *c*³ of the plate member *c*² pass into the slot or opening *b*⁵ of the reinforcing member *b*², and the flanges *c*³ of the plate members *c*² are provided in their rear ends with longitudinal slots or

recesses c^4 which receive the central part b^6 of the front portion b^3 of the reinforcing member b^2 .

The main plate member c , or the separate parts c^2 thereof, are also welded to the front side portion b^3 of the transverse support b^2 , and also welded, or otherwise secured to the sides a^3 of the main body or stock a , and the parts c^2 of the plate member c are separated 10 by a longitudinal slot c^5 , and the block d extends upwardly and fills, or approximately fills, the central portion of said slot.

In the accompanying drawing, reference being made to Figs. 1, 2 and 7, I have shown 15 at e the main cap or wedge plate, at f a supplemental cap or wedge plate and at g a blade, and the plate f and blade g are shown connected but detached from the bridge work in Fig. 5.

20 The plate f is provided with a central longitudinal slot f^2 and a screw h is passed downwardly through the cap or wedge plate e and bears on the plate f rearwardly of said slot, as clearly shown in Fig. 1.

25 The blade g is much shorter than the plate f and a screw i having a milled head is passed downwardly through the slot f^2 in the plate f and into the blade g , as is also shown in Fig. 1, and connects said parts 30 and renders the blade g adjustable on the bottom of the plate f . The blade g rests on the plate c , or the separate parts c^2 thereof and on the block d , and the block d is provided at its rear end with a raised shoulder d^4 , and the plate f rests on the shoulder d^4 which projects slightly above the plate members c^2 and the screw h bears on the plate f rearwardly of the slot f^2 therein.

40 The plate f is provided at its rear end with a laterally directed extension f^3 in which is a longitudinal slot or opening f^4 , and centrally of the rear end portion of said plate, and rearwardly of the slot or opening f^2 is an aperture f^5 .

45 The block d of the central bridge work or blade support is provided with a backwardly directed finger d^5 having an upwardly directed member d^6 on which is mounted a milled screw head j having a grooved collar j^2 , and a lever k is pivoted between the rear ends of the flanges c^3 of the plate member c^2 and provided with an upwardly directed nose k^2 which operates in the aperture f^5 , and the rear end portion 50 of said lever is provided with a forked head k^3 , the side portions of which operate in connection with the grooved collar j^2 of the milled screw head j , and by means of this construction the plate f and blade g may both be adjusted forwardly and backwardly, while the blade g may be independently adjusted on the plate f by means of the screw i , as hereinbefore described.

60 Pivoted at m to one of the plate members c^2 of the plate c is a crank lever m^2 which

ranges transversely and rests on the rear end portions of the plate member c^2 and is provided at its free end with a raised handle m^3 , and said lever is provided at the elbow m^4 thereof with an anti-friction roller m^5 which operates in the slot f^4 in the rear end portion of the plate f , and by means of this construction the lever m^2 may be manipulated so as to adjust the plate f and the blade g laterally. The main cap or wedge 70 plate e is used in the manner of other devices of this class and, in the placing of said plate in position, the front end thereof is passed downwardly under a transverse pin m^6 secured between the side flanges or plates a^3 of the main frame or stock, and with my improvement the main cap or wedge plate e , the supplemental cap or wedge plate f and blade g are all much shorter than these parts, or similar parts, in 80 planes of this class as usually constructed, and the handle n which is attached to the main frame or stock rearwardly of and adjacent to the said parts is higher than the bridge work or support, and its connected parts, and the milled screw j may be manipulated by a finger of the hand which grasps the handle without releasing said handle, if 85 desired.

90 The handle n is detached and is provided with a base plate n^2 which is secured thereto and provided with a downwardly curved front end portion n^3 which bears on the bottom or body part a^2 of the stock and the rear end of said plate is provided with 100 a downwardly and forwardly curved hook member n^4 , and in the practice of my invention I provide a handle securing device o which is shown detached in Fig. 6, and which consists of an oblong plate having downwardly directed side flanges o^2 and an upwardly curved front end portion o^3 in which is formed a screw-hole o^4 rearwardly of which is a transverse slot o^5 , and the handle securing device o is rigidly secured in the main stock or frame and a screw o^6 having a milled head o^7 is passed through the screw-hole o^4 and provided at its front end with a pointed nose o^8 which enters a recess in the front end of the bottom plate n^2 of the handle n , and all that is necessary to connect the handle with the stock is to move said handle forwardly so that the front end portion n^3 will pass through the transverse slot o^5 in the handle securing device o , and so that the rear end hook n^4 of the plate n^2 will engage the rear end portion of the handle securing device o , as shown in Fig. 1, after which the screw o^6 is manipulated to engage the plate n^2 as shown 110 in Fig. 1.

115 In using tools of this class it is frequently necessary to oil the bottom thereof, or the workpiece, and in the practice of my invention I mount on the front end portion of 120

the plane, or the stock thereof, an oil receptacle p of any form of construction and rearwardly thereof, in the construction shown, is placed a lubricant receiving pad 5 p^2 inclosed in a receptacle formed by a transverse rear plate p^3 and a top plate p^4 , the rear end portion of which fits in a transverse groove p^5 in the plate p^3 and the front end portion of which is curved downwardly 10 and provided with a slot p^6 .

The pad p^2 is held in place by wire threads or similar devices p^7 passed therethrough longitudinally and transversely of said pad and through apertures or perforations 15 in the bottom plate a^2 of the main frame or stock as shown at p^8 .

The plate p^4 is flexible and vertically movable and the front end portion thereof is provided with side ears p^9 having vertical slots p^{10} and headed pins p^{11} are passed through the slots p^{10} and into the side plates or flanges a^3 of the main frame or stock, this construction being clearly shown in Figs. 1, 2, 3 and 9.

25 The oil receptacle p is provided with a bottom tube p^{12} which passes through the slot p^6 in the front end of the top or cover plate p^4 of the lubricating pad receptacle, and in the bottom of the oil receptacle p is pivoted a lever p^{13} , one end of which is provided with a valve p^{14} which is adapted to open and close the end of the tube p^{12} , and with the other end of which is connected a spring p^{15} which normally holds the valve p^{14} in a closed position, and connected with the lever p^{13} opposite the valve p^{14} is a rod p^{16} which extends upwardly through a transverse support p^{17} in the top portion of the receptacle p and is movable therethrough, and the rod p^{16} is provided at its upper end with a head p^{18} , and the receptacle p with a flexible cover p^{19} which bears thereon, and by applying pressure to the head p^{18} of the receptacle p the valve p^{14} will be opened and the lubricating material 40 will pass from the receptacle p into the pad p^2 and from said pad p^2 through the apertures or perforations p^8 to the bottom of the plane, or the stock thereof and onto the 45 workpiece, and this operation may be facilitated by pressure applied to the top plate p^4 of the receptacle in which the lubricating pad p^2 is placed.

50 In Fig. 1 of the accompanying drawing, I have shown the receptacle p mounted in and forming a part of the ordinary supplemental knob handle p^{20} of a plane but in Fig. 3 the lubricating or oiling receptacle is mounted independently of said handle, but my invention is not limited to any particular means of mounting or applying the lubricating receptacle nor to a lubricating receptacle of any particular form or construction.

55 When the form of construction shown in

Fig. 1 is employed, the receptacle p is provided with a bottom screw pin p^{21} which passes downwardly through the bottom of the handle p^{20} and an angle piece p^{22} is secured to the bottom of the frame or stock 70 and fits in a corresponding recess in the bottom of the handle to prevent said handle from turning in the manipulation of the plane, and in the construction shown in Fig. 3, the parts p^{21} and p^{22} are also employed 75 but the part p^{22} will have no function except when the handle p^{20} is employed, unless it be to form an additional support for the receptacle p and the pin p^{21} .

The rear end of the main cap or wedge 80 plate e is curved backwardly and downwardly as shown in Fig. 1, and the side edges thereof are brought together and tapered backwardly to form a projecting finger piece e^2 , and in the use of the plane 85 the front finger of the hand which grasps the handle is used in connection with said finger piece to guide the plane.

I also provide means whereby my improved plane may be used as a level, and 90 this means comprises a spirit level tube r which is mounted between the handle and the adjacent side plate a^3 of the frame or stock, said side plate a^3 is provided with a sight opening r^2 and the spirit level tube r 95 may be read from above or from the aperture r^2 as may be desired, and the spirit level tube is also provided with a sleeve r^3 which is slidably mounted thereon and by means of which the glass in the tube may be 100 protected from injury when the plane is packed in a tool chest, or at any other time.

I also provide means whereby my improved plane may be used as a plumb, said means comprising a spirit level tube s 105 mounted transversely of the frame or stock of the plane rearwardly of the handle and as clearly shown in Figs. 1 and 2, and the operation of this device for the purpose specified will be readily understood, and mounted 110 on the spirit level tube s is a rotatable sleeve s^2 having an opening which corresponds with the opening in the tube and by means of which the glass in the tube may be 115 protected against breakage, when desired.

The top surface of the central block d of the blade support or bridge work is provided with a longitudinal recess d^7 to receive the point of the screw i and to permit of its free operation and also to permit of the adjustment of the blade g and supplemental wedge plate on said block.

I also provide means whereby my improved plane may be used as a square, and for this purpose I secure in the rear end portion of the main frame or stock a transverse locking device u having a raised central portion u^2 through which is passed a lock plate u^3 provided at its front end with a thickened head u^4 in the top of which is a recess 125

u⁵, and the rear end of the lock plate *u³* is provided with a downwardly directed lip *u⁶* and, in practice, an ordinary carpenter's rule *w* having a groove *w²* on one side of its rear edge portion is passed transversely through the rear end of the main frame or stock as shown in Fig. 10, and also in Figs. 1 and 2, and the lip *u⁶* of the lock plate *u³* fits in the groove *w²* and the front end part of the raised central portion *u²* of the lock device *u* is raised as shown at *u⁷* and a screw *x* having a milled head *x²* is passed downwardly through the part *u⁷* and into the recess *u⁵*, and this screw serves to force the lock plate *u³* forwardly and to bind or lock the rule *w* in position, and the use of my improved plane as a square will be readily understood by all those familiar with the operation and use of this class of devices.

20 By constructing the bridgework, and connected parts, as herein shown and described, whereby said bridgework and connected parts including the blade and cap plates are comparatively low and providing a detachable handle which may be quickly and easily attached or detached when desired, I provide means whereby the plane may be packed in a small space for shipment or other purposes by simply detaching the handle, and while I have shown and described specific means whereby the handle may be quickly and easily detached and quickly and easily applied for use as desired, this feature of the invention is not claimed herein but is made the subject of a divisional application filed July 12, 1916, Ser. No. 108,792.

Having fully described my invention, what I claim as new and desire to secure by 40 Letters Patent, is:—

1. In a carpenter's plane, a main frame or stock and a blade support or bridge work, consisting of a triangular part arranged transversely of the frame or stock and the apex of which is directed upwardly and provided with a central transverse slot which ranges forwardly and backwardly, a block secured in said slot and ranging upwardly and backwardly, a blade supporting 45 top plate placed on the triangular support and ranging upwardly and backwardly, said plate being composed of two similar parts separated by a central longitudinal slot into which the top part of the block passes, 50 the parts of said plate being provided at their inner edges with downwardly directed flanges between which said block fits and said flanges being provided at their front ends with slots to receive the front part of the triangular support, all of said parts being rigidly connected and rigidly secured in the main frame or stock.

2. In a carpenter's plane, a main frame or stock and a blade support or bridge work, 60 consisting of a triangular part arranged

transversely of the frame or stock and the apex of which is directed upwardly and provided with a central transverse slot which ranges forwardly and backwardly, a block secured in said slot and ranging upwardly and backwardly, a blade supporting plate placed on the triangular support and ranging upwardly and backwardly, said plate being composed of two similar members separated by a central longitudinal slot corresponding with the top of the block, the parts of said plate being provided at their inner edges with downwardly directed flanges between which said block fits, and said flanges being provided at their front ends with slots to receive the front part of the triangular support, all of said parts being rigidly connected and rigidly secured in the main frame or stock.

3. In a plane, a blade, a cap plate mounted on said blade and longer than said blade and extending rearwardly thereof and provided with a central longitudinal slot, a screw passed downwardly through said slot into said blade, said cap plate being also provided in its central rear end portion with an aperture at one side of which is a longitudinal slot, means operating in said aperture to adjust the plate and blade longitudinally, and means operating in said slot to adjust said plate and blade laterally.

4. A plane provided with a short and low bridge-work having an upwardly and backwardly inclined top surface at the rear end of which is a raised member, a blade mounted on the surface of the bridgework forwardly of said member, a supplemental cap plate mounted on said blade and on said bridgework and extending rearwardly thereof and provided with a central longitudinal slot, a screw passed downwardly through said slot into said blade whereby said blade may be longitudinally adjusted with reference to said supplemental cap plate, a main cap plate mounted over the supplemental cap plate, and a screw passed downwardly therethrough and bearing on the supplemental cap plate rearwardly of the blade.

5. A plane provided with a short and low bridge-work having an upwardly and backwardly inclined top surface at the rear end of which is a raised member, a blade mounted on the surface of the bridgework forwardly of said member, a supplemental cap plate mounted on said blade and on said bridgework and extending rearwardly thereof and provided with a central longitudinal slot, a screw passed downwardly through said slot into said blade whereby said blade may be longitudinally adjusted with reference to said supplemental cap plate, a main cap plate mounted over the supplemental cap plate, and a screw passed downwardly therethrough and bearing on the supplemental cap plate rearwardly of the blade,

5 said supplemental cap plate being also provided in its rear end portion with a central aperture at one side of which is a longitudinal opening, and means operating through said aperture to adjust the supplemental cap plate and blade longitudinally, and means operating through said opening to adjust said parts laterally.

6. A plane provided with a short and low 10 bridgework having an upwardly and backwardly inclined top surface at the rear end of which is a raised member, a blade mounted on the surface of the bridgework forwardly of said member, a supplemental cap 15 plate mounted on said blade and on said bridgework and extending rearwardly thereof and provided with a central longitudinal slot, a screw passed downwardly through

said slot into said blade whereby said blade may be adjusted longitudinally of said cap plate, a main cap plate mounted over the supplemental cap plate, a screw passed downwardly therethrough and bearing on the supplemental cap plate rearwardly of the blade, means for adjusting the supplemental cap plate and blade longitudinally, and means for adjusting said parts laterally.

20 In testimony that I claim the foregoing as my invention I have signed my name in presence of the subscribing witnesses this 25 27th day of September, 1915.

GEORGE D. YOUNG.
